UNITED STATES PATENT OFFICE.

SIMON WREATON BENSON, OF CHICAGO, ILLINOIS.

METALLIC-FRAMED WINDOW-SCREEN.

No. 864,224.

Specification of Letters Patent.

Patented Aug. 27, 1907.

Application filed May 8, 1905. Serial No. 259,256.

To all whom it may concern:

Be it known that I, SIMON WREATON BENSON, a citizen of the United States, residing at Chicago, in the county of Cook and State of Illinois, have invented 5 certain new and useful Improvements in Metallic-Framed Window-Screens, of which the following is a description.

My invention relates to window screens and the like, particularly metallic framed screens, and has for 10 its object the production of a simple, durable and inexpensive screen for the purposes for which such like screens are usually employed.

The frame of my screen is preferably made of metal, galvanized steel being quite suitable, so that it will 15 not shrink, swell, warp, check, rot or wear out. The parts of the frame may be made in long lengths and shipped in bundles, and then cut into the shorter lengths for screens as may be desired when the various parts are assembled and fitted in place, thus 20 reducing freight rates considerably. Owing to the great simplicity in assembling the frame and fastening the screen wire in place, the assembling and fitting may be done by unskilled persons. My screen either 25 slides or swings, depending on the means for fastening in place. It is particularly adapted to be used in narrow or limited places where a screen is desired, as for instance where outside blinds are used. It may be used on the lower or on the upper part of an opening or window or on both at the same time, and in 30 every case always fits tight in place.

To this end my invention consists of the novel construction, arrangement and combination of parts herein shown and described, and more particularly pointed out in the claims.

35 In the drawings wherein like reference characters indicate like or corresponding parts. Figure 1 is a partial view of a window in elevation, showing a screen in position. Fig. 2 is a vertical section of the same. Fig. 3 is a partial longitudinal sectional view, showing 40 a modified form of screen as applied where space is limited. Fig. 4 is an elevation view of the frame. Fig. 5 is a cross-sectional view taken on line 5—5 of Fig. 4. Fig. 6 is a detail section taken on line 6—6 of Fig. 7, showing the locking device. Fig. 7 shows the 45 lock in elevation, the lock being closed. Fig. 8 shows the preferred form of catch as applied to the sill of the window. Fig. 9 is a section taken on line 9—9 of Fig. 7. Fig. 10 is a section taken on line 10—10 of Fig. 7. Fig. 11 is a detail view, a portion of the frame being broken away. Fig. 12 is a modified form of 50 the rail and clamp, and Fig. 13 shows the locking lever.

Referring now to the drawings, my screen consists of rails 1, 2, and side rails 3, preferably secured together by means of corner pieces 4 and bolts, screws 55 or rivets 17 and 18, and a wire fabric 5, the wire fabric being held in place by means of the frame rails and

the clamping members 7. The rails are preferably formed as at 6, and provided with flange 8. The flanges 8 are adapted to bear against the frame of the window as at 9 and 10, or against other suitable stops. 60 In Fig. 5, the upper rail is shown with the flanges 8 extended as at 16, 13 and 15, making an adjustable filling member, that is it may be easily bent into a position covering the opening between the flanges 8 of the upper rail and the window sash 14. 65

The rails or frame members 6 are preferably bent into a form similar to that shown at 11, and provided with catches 12, so that these catches and the bent portions 11 hold the clamping members 7 in place, thus gripping and holding the fabric 5 firmly. The preferred construction of the catches is clearly shown in the drawings, a portion 12 of the rails 6 being partially cut out and turned down. The fabric is placed in position, the edges extending into the bent part 11, and then the clamping members 7 either sprung into place or 70 forced endwise in between the bent portion and the catches. While the preferred way is to spring or force, and thus secure the clamping member into place as before mentioned, it is obvious that bolts 24, rivets or the like may be also employed if desired to hold the 75 plate 7 in place.

To secure my screen in place before a window or other opening, I preferably use hooks similar to 23, and provide extensions on the corner pieces 4 by bending up the portion 20 as at point 22. The corner pieces 85 4 are preferably bent as at 19 and extend over the bent portion 6 of the frame rails. To strengthen the extensions 20 and give greater leverage in the hook when the frame is in place before the aperture I have flanged the extensions 20 as at 21. In Fig. 7 is shown my preferred 90 way for forcing the screen up tight against the stops and locking it in place.

The locking means is most clearly understood by referring to Figs. 6, 7 and 8, in which 9 is the window sill, having secured to it the preferred form of catch 31. 95 This catch has a portion of the base cut and turned down, the turned down portions being driven into the sill, thus strengthening and preventing the catches from turning about their fastenings. A seat or bench 32 is provided, upon which is seated the end 25 of the lever 27, the lever and bench being held preferably by the bolts 35 and nut 34, arranged so that as the lever is swung the nut will not tighten or loosen. The lever 27 is preferably bent as at 29, and provided with the extension 30. An extension 26 provided with the cam face 28, is likewise arranged on the part 25 of the lever and is adapted to engage the catch 31, thus drawing the screen frame up tight against the window frame or other suitable stops when the lever is operated. The end of the lever at 30 is held from dropping when the 105 catch is disengaged, by the extended part 30 coming in contact with the frame. It is obvious that any num-

ber of locking means may be put on as required or as desired.

As is shown in Fig. 3, a very convenient way of arranging the screen in place when the space is limited, 5 is by flanged members 37 and the long headed nuts or screws 38. A modification of the screen is also shown in Fig. 12.

It is obvious that various immaterial modifications may be made in my device as by leaving off the extensions 10 when the sliding arrangement is used, or leaving off the bottom extension when the screen is placed before the upper part of an opening as is shown in dotted line in Fig. 2.

Having thus described my invention what I claim 15 as new, and desire to secure by Letters Patent is:

1. In a device of the kind described, a screen frame consisting of substantially partially cylindrical face plates, each flanged at one edge and folded to form a channel at the opposite inside edge, a portion of said face plates at 20 the edges opposite the channels turned inwardly to form catches, and clamping plates adapted to engage the face plates in the said channels and at the catches, in combination with a fabric, said fabric having a portion thereof arranged in said channels and retained therein 25 by said clamping plates.

2. In a device of the kind described, a screen frame, consisting of substantially partially cylindrical face plates, each flanged at one edge and folded to form a channel at the opposite inside edge, a portion of said face plates at 30 the edges opposite the channels turned inwardly to form

catches 12, the flange of one plate extended to form a filling plate, and clamping plates, in combination with a fabric, said fabric having a portion thereof arranged in said channels and retained therein by said clamping plates.

3. In a device of the kind described, a screen frame 35 consisting of substantially partially cylindrical face plates, each flanged at one edge and folded to form a channel at the opposite inside ends, a portion of said face plates at the edges opposite the channels turned inwardly to form 40 catches 12, the flange of one plate extended to form an adjustable filling plate, corner plates for securing the face plates together, in combination with a fabric, a portion of said fabric arranged in said channels and retained therein by said clamping plates.

4. In a device of the kind described, a screen frame 45 consisting of substantially semi-cylindrical flanged face plates each folded to form a channel at the edge opposite the flange and provided with catches at the flanged edge, the flange of one face plate extended to form a filling plate, corner plates for securing the face plates together, 50 a portion of said corner plates being provided with extensions for securing the frame in place, and clamping plates, in combination with a fabric, said fabric having a portion thereof arranged in said channels and retained therein by said clamping plates, and means for holding the frame 55 in position.

In testimony that I claim the foregoing as my own, I have hereunto affixed my signature in the presence of two witnesses.

SIMON WREATON BENSON.
